(74) Attorney, Agent, or Firm—Paul W. Garbo

CLAIM

The ornamental design for a foil tray, as shown and described.

DESCRIPTION

FIG. 1 is a top plan view of a foil tray showing my new design;

FIG. 2 is an elevational view thereof; and,

FIG. 3 is a sectional view taken from line 3—3 of FIG. 1. The claimed foil try could be used for food shaped like an inverted pizza shell.
